UNITED STATES PATENT OFFICE.

JOHN F. YOUNG, OF BROOKLYN, ASSIGNOR TO FRIEDRICH PANSE, OF NEW YORK, N. Y.

PLAITING-MACHINE.

SPECIFICATION forming part of Letters Patent No. 370,843, dated October 4, 1887.

Application filed March 12, 1887. Serial No. 230,595. (No model.)

To all whom it may concern:

Be it known that I, JOHN F. YOUNG, a citizen of the United States, residing at Brooklyn, in the county of Kings, State of New York, 5 have invented a new and Improved Plaiting-Machine, of which the following is a specification.

This invention relates to a machine for making plaited and other folded goods, and which 10 is provided with mechanism for sewing the plaits or other folds together when formed. The machine is so constructed that the sewing devices and the feeding devices operate intermittently and not continuously, and thus a 15 number of plaits may be formed and superposed before being sewed together. In this way a variety of patterns may be produced which cannot be made in machines that sew continuously.

20 The invention consists in the various features of improvement more fully pointed out in the following description and claims.

In the accompanying sheets of drawings, Figure 1 is a side elevation of the machine 25 with the overhanging needle-arm removed. Fig. 2 is a vertical transverse section on line $x-x$, Fig. 5. Fig. 3 is a detail view of part of the driving-shaft. Fig. 4 is a bottom view of the main part of the machine. Fig. 5 is a top view 30 of the machine without the needle-arm. Fig. 6 is a longitudinal section on line $y-y$, Fig. 5. Fig. 7 is a perspective view of the machine.

The letters a a' represent a pair of gage-plates, of which the plate a receives up-and-down motion, while the plate a' receives up-and-down motion as well as reciprocating motion. Between these plates the fabric placed on feed-table b is folded or plaited, as is well known. The motion of plate a' is received 35 from work-shaft c through gear-wheel d and connecting-links e e , while the plate a' in turn operates plate a by pins f , attached to plate a' . A presser-foot, g , placed between the gage-plates, descends every time the gage-plates are 40 at their greatest proximity, to bind the folded fabric in place. This presser-foot is operated by a cam, h , on a transverse shaft, i , that receives motion by gear-wheel d from work-shaft c .

45 The parts thus far described operate substantially as described in Patent No. 331,432,

granted to F. Panse, December 1, 1885, and are not the subject of the present invention.

This invention consists, essentially, in the employment of a looper and a feed-bar that are 55 alternately put in and out of motion, the motion being imparted to these parts when the plate a' recedes from the plate a to come into position for the formation of one or more new folds.

60 To carry this invention into effect the machine is constructed as follows:

To the shaft i there is affixed a cam, j , against the face of which there is held one end of a pivoted bar, k . This bar is perforated for the 65 admission of a tubular shifting clutch, l , surrounding one end of work-shaft c , and adapted to engage a counterpart shoulder, m , on work-shaft c , the faces of the coupling members 70 having coacting projections and interdental spaces.

To the end of clutch l there is connected a shaft, n , upon which are mounted the looper and the cams for operating the feed-bar, as is 75 hereinafter described.

l' is a shoulder upon clutch l and bearing against one side of pivoted bar k , against which it is pressed by a spring, l'' , and in this way the end of the pivoted bar is held against the working-face of the cam j .

80 By means of the parts thus far described the clutch l is reciprocated upon the work-shaft c —that is to say, when the bar k bears against the protruding surface of the cam j the bar will be pressed against shoulder l' to compress 85 the spring l'' and to keep the clutch out of engagement with its counterpart shoulder m ; but when the bar k is brought opposite the receding surface of the cam j the spring l'' will be at liberty to throw the clutch l into engagement with shoulder m . The result will be that the rotary motion of the shaft c will be transmitted to the clutch l and with it to the looper-carrying shaft n , while when the clutch is out of engagement such shaft n will receive no motion. The surface of the cam j may be made in a variety of shapes, so as to operate the clutch at any desired period. Thus the clutch may be thrown into engagement after the machine has shaped one fold between its gage- 95 plates or after it has shaped two or more folds.

100 Upon the shaft n there is mounted the looper

o or needle-hook; operating in conjunction with the needle to form the stitches whenever the looper is revolved. The shaft *n* also carries the cam or cams for reciprocating and raising and lowering the feed-bar *p*. This feed-bar projects through a slot in the work-table, as usual, and is attached to a slotted slide, *q*, engaged by two cams, *r s*, on shaft *n*. This slide turns upon a pivot, *t*, and is moved backward by the cam *r*, while it is thrown forward by spring *u*. The up-and-down motion of the feed-bar is imparted to it from slide *q* by means of the cam *s*. When the clutch *l* is out of engagement with the working-shaft, the looper and the feed-bar will be at rest; but when the clutch is revolved by engagement with the work-shaft it will revolve the looper *o* and the cams *r s*, thus causing the formation of the stitch and the proper presentation of the work to the needle.

What I claim is—

1. The combination, in a plaiting-machine, of a shaft, *c*, with a looper-carrying clutch and with a pair of gage-plates and links for transmitting motion to the gage-plates from the shaft, and with a cam and a pivoted bar operated by the cam and adapted to throw the clutch alternately into and out of engagement with the shaft *c*, substantially as specified.

2. The combination, in a plaiting-machine, of the following elements: a work-shaft, a clutch, a looper, and feed-bar connected to the clutch, a cam, a pivoted bar bearing against the cam for operating the clutch, and gage-plates for forming the plaits, and means whereby the revolution of the cam causes intermittent engagement of the clutch with the shaft, substantially as specified.

3. The combination, in a plaiting-machine, of a work-shaft, a clutch mounted thereon, a feed-bar and looper connected to the clutch, a spring surrounding the clutch, a cam revolved by gearing from the work-shaft, a pivoted bar for transmitting motion from the cam to the clutch, and gage-plates for forming the plaits, substantially as specified.

4. The combination, in a plaiting-machine, of the following elements: gage-plates operated from a shaft connected to a cam, a work-shaft carrying a clutch, an intermediate pivoted rod, a looper connected to the clutch, and a pair of cams connected to the clutch and operating a slide carrying the feed-bar, substantially as specified.

JOHN F. YOUNG.
